DESIGN FOR WRAPPING PAPER OR SIMILAR ARTICLE

Homer M. Sinclair, Holyoke, Mass., assignor to American Tissue Mills, Holyoke, Mass., a corporation of Massachusetts

Application February 25, 1939, Serial No. 83,210

Term of patent 14 years

To all whom it may concern:

Be it known that I, Homer M. Sinclair, a citizen of the United States, residing at Holyoke, in the county of Hampden and State of Massachusetts, have invented a new, original, and ornamental Design for Wrapping Paper or Similar Article, of which the following is a specification, reference being had to the accompanying drawing, forming part thereof.

The figure is a plan view of wrapping paper or similar article showing my new design.

The design consists of wrapping paper having color lines or stripes which are in contrast with the color of the background as shown.

I claim:

The ornamental design for wrapping paper or similar article, as shown and described.

HOMER M. SINCLAIR.
